UNITED STATES PATENT OFFICE.

LOUIE BORTKEWICZ, OF RACOON STATION, PENNSYLVANIA.

BIT-FORGING MACHINE.

Application filed July 15, 1925. Serial No. 43,675.

This invention relates to a die forging machine, and particularly to a die forging machine for use in making or reforging cutter bits for undercutting machines used in coal mines and the like.

One object of the invention is to provide a machine in which a cutter bit, or generally similar article, is formed by a succession of relatively light blows, thus obviating the necessity for subjecting the stock to a considerable pressure, and resulting in the production of a true forging at each operation.

A further object of the invention is to provide a die forging machine in which a plurality of movable dies are actuated by simple connections and from a single moving part, and which is so arranged as to embody few and simple adjustments.

Another object of the invention is to provide a die forging machine of the character indicated, which may be utilized successfully by an unskilled operator.

A still further object of the invention is to provide means associated with, and operated by, the die forging mechanism proper for tempering finished articles which have been forged by the machine.

In the accompanying drawings Figure 1 is a side elevation of the machine of the present invention; Figure 2 is a plan view of the same; Figure 3 is a front elevation of the machine; Figure 4 is a fragmentary vertical sectional view on the line 4-4 Figure 3; Figure 5 is a cross sectional view, taken on the diagonal section line 5-5 of Figure 4; Figure 6 is an isometric view of a stock from which a cutter bit is to be forged, and Figure 7 is an isometric view of a completed cutter bit.

The machine comprises a bed or table 1 supported by a frame 2. A driving shaft 3 is mounted transversely of the bed or table in bearings 4, and is provided at both ends thereof with pulleys 5. In use of the machine one of the pulleys is connected with a source of power, while the other acts as a balance wheel for the shaft.

A slide bar 6 is mounted for reciprocating movement in brackets 7 and 8 of the table 1. The rearward extremity of the slide bar 6 is operatively connected with the driving shaft 3 of the machine. These connections comprise a link 9 connecting the end of the slide bar with a pivoted rod 9^a, which is pivotally secured to the end of a pitman

10. At its forward extremity pitman 10 has an eccentric connection 11 with the driving shaft 3 of the machine, so that rotation of the shaft produces reciprocating movement of the sliding bar 6.

The means for positioning stock to be forged comprises a slide bar 12 which is normally maintained in its rearward position in the machine by means of a coiled spring 65 13. Secured to the slide bar 12 is a block or stock holder 14, which has a hollowed portion 15 for the reception of a stock or bit to be forged. At its rear, this hollowed portion 15 is bounded by a curved member 70 or bar 16, which extends forwardly and downwardly of the machine.

The means for operating the sliding bar 12, and its associated elements, comprise a treadle 17, which is pivoted at 18 in the frame 2 of the machine. Treadle 17 is connected by a rod 18^a with one arm 19^a of a bell crank 19, which is pivoted at 20 in the frame 2. The other arm 19^b of the bell crank bears against the rearward extremity 80 of the block, or stock holder, 14 for forcing this member and slide bar 12 forwardly. Pivotally mounted in block 14 is a feed bar 21, having an operating handle 22. This bar is arranged to bear against the inner 85 surface of the curved member 16.

Adjacent the forward extremity of table 1 is a stationary die holder 23, in which is secured a stationary die 24.

To feed the stock, treadle 17 is depressed, 90 producing forward movement of slide bar 12, and stock holder 14, against the resistance of coiled spring 13. A stock 25, or bit to be reforged 26, is then dropped into the hollowed portion 15 of the block 14, and allowed to pass downwardly along the feed bar 21 to the curved member 16. If a piece of stock 25 is to be formed into a cutter bit, one corner 25^a is previously bevelled off. When the stock has been inserted in the feeding mechanism, treadle 17 is released 95 and the slide bar 12, carrying stock holder 14, is moved back to operative, or forging position by the coiled spring 13.

During this action the extremity of feed bar 21 remains in contact with the forward surface of the curved member 16. Forward or outward movement of the operative extremity of the feed bar, to cause accidental discharge of the stock from the feeding mechanism, is prevented by means 100 of a U-shaped arm 27 which is pivoted at 110

the points 28 to the stock holder. Lever 27 is maintained in rearward position by means of coiled springs 29 secured to the frame 2, and has a lug 27^a which projects into the 5 path of movement of feed bar 21 for resisting outward movement of the latter. When the stock has been inserted, handle 22 is depressed, to slide the stock upwardly along the surface of curved member 16 and 10 through an aperture 20 in die 24 into forging position. The stock is maintained in this position during the forging operation by a continued depression of the handle 22, which maintains the feed bar 21 in position 15 to hold the stock in the die 24.

With the stock positioned in die 24, it is 20 acted upon by a die 31, which is adjustably mounted in the forward portion of slide bar 6 by means of a set screw or the like 32. During the forging operation the stock 25 is acted upon not only by the stationary die 24, and the die 31 carried by the slide bar; but is also acted upon by a pair of dies 33, which have shanks 33^a extending through apertures 34 in the table or bed 1. These shanks 33^a are pivoted at 35 to the frame of the machine. These pivoted dies 33 are positively actuated so that they perform a hammering action on the stock being 30 forged.

The operating connections for the pivoted dies 33 are so arranged that these dies are 35 actuated by movement of the slide bar 6. For this purpose two actuating arms 36 are mounted for oscillatory movement at the points 37 in the bracket 8. Adjacent the rearward extremity of each arm is a notch 38 in which a hook shaped contact member 39 has a pivotal mounting 40. Projecting through each of the arms 36 40 and bearing against the hooked contact members 39, are adjusting screws 41 for regulating the extension of the contact members inwardly from the arms. On the 45 slide bar 6 are a pair of contact arms 42 which are pivotally mounted at 43, and which extend outwardly from and rearwardly of the slide bar 6. Adjacent their rearward extremity each of the actuating 50 arms 36 is provided with a lug 44 which has a rounded surface for contacting the outward face of that one of the dies 33 to be actuated by that particular arm. Leaf springs 45, arranged to bear against the 55 shank 33^a of each of the dies, exert a force tending to press the dies outwardly from the stock.

After forward movement of the sliding bar 6, which carries the die 31, the slide bar 60 moves rearwardly. During this rearward movement the pivoted contact arms 43 on the slide bar come in contact with the hooked contact members 39 on the actuating arms 36. This movement forces the 65 rearward ends of the arms outwardly, the

extent of their outward movement being increased by the tendency of the contact arms 43 to assume a position perpendicular to the sliding bar. This oscillation of the actuating arms 36 causes their rearward portions to 70 force the pivoted dies 33 inwardly against the stock. As the slide bar again moves forwardly to bring the die 31 into contact with the stock the leaf springs 45, which bear against the shanks of the dies 33, force 75 the dies outwardly and oscillate the actuating arms 36 back to position in the path of the contact arms 43 on the slide bar 6.

When the forging operation has been completed, the handle 22 is forced rearwardly, 80 so that the feed bar 21 is swung outwardly against the lug 27^a on arm 27. This permits the finished work to fall through aperture 20 and along the surface of the curved guide member 16, and to drop into a delivery chute 46.

Special means for tempering the work as it is finished are associated with the die forging mechanism proper. Such means comprise a pressure tank 47 for containing water, or any suitable tempering liquid. From tank 47 lead a liquid pipe 48 and a valved fluid pressure pipe 49. These pipes are both connected with a spray pipe 50, which is disposed adjacent the discharge 55 extremity of the chute 46 in position to deliver a tempering spray to forgings discharged by the chute. Pressure is maintained in the tank 47 by means of a duct 51, which leads to a fluid compressor 52 60 mounted on the table or bed 1. The compressor 52 is mounted in alignment with the slide bar 6, and its piston or plunger 53 is connected by means of piston rod 54 with the slide bar adjacent the rearward 65 extremity of the latter.

Reciprocation of the slide bar 6 thus produces three effects in general operation: first it causes the die actually carried by the slide bar to act upon the stock; second it produces actuation of pivoted side dies, causing them also to act on the stock; third it compresses fluid for delivering a tempering spray to the completed forgings.

The only adjustments required by the mechanism are the longitudinal adjustment of the die 31 in the slide bar 6, and the adjustment of the contact members 39 in the actuating arms 36. These adjustments compensate for wear on the face of the die, the size of the stock, or may be made to regulate the force of the blows delivered during each reciprocation of the slide bar.

If the machine be placed close to a forge, a single operator may easily conduct the 125 entire operation. It is merely necessary to operate the proper handles, and to release the forging when completed. The tempering spray may be delivered continuously during the operation of the machine, so that it 130

requires no attention on the part of the operator. As the forging is effected by a succession of relatively light blows, the stock may be watched, and released at the proper 5 moment without interrupting the movement of the sliding bar. This results in the production of forgings of uniform excellence.

What I claim is:

1. In a forging machine the combination 10 of a stock holder a reciprocable die holder, pivotally mounted dies, and connections arranged to produce action of the pivoted dies on the stock during movement of the reciprocable die holder away from the stock.

15 2. In a forging machine the combination of a stock holder, a sliding bar, pivoted arms arranged to be oscillated by reciprocation of the sliding bar during movement of the sliding bar away from the stock, and dies arranged to be actuated by said pivoted arms 20 to act upon the stock.

25 3. In a forging machine the combination of a sliding bar having a die thereon, a slide- able stock holder, resilient means for main- taining said stock holder in operative position in the path of said sliding bar, and means for moving the stock holder into charging position against the resistance of said resilient means.

30 4. In a forging machine the combination of a sliding bar having a die thereon, a slide- able stock holder, resilient means for main- taining said stock holder in operative position in the path of the sliding bar, connec- 35 tions for moving the stock holder into charging position against the resistance of said resilient means, and means for positioning stock in said holder in the path of said sliding bar.

40 5. In a forging machine the combination of a sliding bar having a die thereon, a slide- able stock holder, means for moving the stock holder between charging position and its operative position in the path of the sliding bar, and cooperating dies arranged to be actuated by movement of the sliding bar.

45 6. In a forging machine the combination of a sliding bar having a die thereon, a slide- able stock holder, resilient means for main- taining said stock holder in operative position in the path of said sliding bar, means for moving the stock holder into charging position against the resistance of said resilient means, and cooperating dies arranged 55 to be actuated by movement of the sliding bar.

70 7. In a forging machine the combination of a sliding bar having a die thereon, a slide- able stock holder, resilient means for main- taining said stock holder in operative position in the path of the sliding bar, connec- 60 tions for moving the stock holder into charging position against the resistance of said resilient means, means for positioning stock in said holder in the path of the slide-

ing bar, and cooperating dies arranged to be actuated by movement of the sliding bar.

75 8. In a forging machine the combination of a sliding bar having a die thereon, a slide- able stock holder, resilient means for main- taining the stock holder in operative position in the path of the sliding bar, means for moving the stock holder into charging position, pivoted dies, and connections arranged to produce action of the pivoted dies on the stock during recessive movement of the sliding bar.

80 9. In a forging machine the combination of a sliding bar having a die thereon, a slide- able stock holder, resilient means for main- taining the stock holder in operative position in the path of the sliding bar, pivoted dies, and connections arranged to transmit movement of the sliding bar to the pivoted dies for actuating the same.

85 10. In a forging machine the combination of a sliding bar having a die thereon, a slide- able stock holder, resilient means for main- taining the stock holder in operative position in the path of the sliding bar, pivoted arms arranged to be oscillated by reciprocation of the sliding bar, and dies arranged to be actuated by said pivoted arms to act upon the stock.

90 11. In a forging machine the combination of a sliding bar having a die thereon, a slide- able stock holder, means for moving the stock holder between charging position and its operative position in the path of the sliding bar, pivoted arms arranged to be oscillated by reciprocation of the sliding bar, and dies arranged to be actuated by said pivoted arms to act upon the stock.

95 12. In a forging machine the combination of a reciprocable die holder, a stock holder, contact members on said die holder, pivoted arms having portions extending toward the path of movement of the reciprocable die holder for producing oscillation of the arms during movement of the die holder away from the stock holder, and pivotally mounted dies arranged to be actuated by oscillation of such arms to act upon the stock.

100 13. In a forging machine the combination of a reciprocable die holder, a stock holder, pivoted arms having portions extending toward the path of movement of the die holder, contact members pivotally mounted on said die holder for contacting the extending portions on the arms and oscillating the arms during movement of the die holder away from the stock holder, and pivotally mounted dies arranged to be actuated by said pivoted arms to act upon the stock.

110 14. In a forging machine the combination of a reciprocable die holder, contact mem- bers on said die holder, a stock holder, pivoted arms having adjustable members thereon extending toward the path of move- 120 ment of the die holder for producing oscil- 130

lation of the arms during movement of the die holder away from the stock holder, and pivotally mounted dies arranged to be actuated by oscillation of the arms to act upon the stock.

15. In a forging machine the combination of a reciprocable die holder, a stock holder, pivoted arms, adjustable contact members on said arms extending toward the path of movement of the die holder, pivoted contact members on said die holder arranged to engage the contact members on the arms for oscillating the arms during movement of the die holder away from the stock holder, and pivotally mounted dies arranged to be actuated by oscillation of the arms to act upon the stock.

16. In a die forging machine a stock holder comprising a downwardly extending guide member having a surface arranged for the feeding of stock, side members, and a movable feed-bar arranged to cooperate with the feed surface of said guide member.

17. In a die forging machine a stock holder comprising a downwardly extending guide member having a curved surface for the feeding of stock, side members, and a pivotally mounted member so arranged that

during oscillation thereof its extremity is in contact with the curved surface of the guide member.

18. In a die forging machine a stock holder comprising a downwardly extending guide member having a surface arranged for the feeding of stock, side members, a movable feed bar arranged to cooperate with the feed surface of said guide member, and yielding means for normally preventing movement of the operative end of the feed bar outwardly beyond the extremity of the guide member.

19. In a die forging machine a stock holder comprising a downwardly extending guide member having a curved surface for the feeding of stock, side members, a pivotally mounted member so arranged that during oscillation thereof its extremity is in contact with the curved surface of the guide member, and yielding means for normally preventing oscillation of the feed member into position with its extremity beyond the extremity of the guide member.

In witness whereof, I hereunto set my hand.

LOUIE BORTKEWICZ.
